UNITED STATES PATENT OFFICE.

JAMES A. MUZZIO, OF CLEVELAND, OHIO, ASSIGNOR TO ROSA S. MUZZIO, OF CLEVELAND, OHIO.

LOCKING MECHANISM.

Application filed May 25, 1923. Serial No. 641,391.

This invention relates to locking mechanism and more particularly to cylinder locks. The invention is an improvement upon the construction described and claimed 5 in my prior application for locking mechanism, filed January 2, 1923, Serial No. 610,202.

Said prior application illustrates cylinder locking mechanism in which the rotatable plug and stationary barrel or cylinder are concentrically related and provided with a special roll-back mechanism, the parts of which may be withdrawn or retracted within the outer cylindrical boundary of the 15 barrel to enable the barrel to be inserted into lock mechanism and wherein rotation of the plug throws the roll-back or dog outwardly beyond the boundary of the cylinder for actuation of the dead bolt or other device. In 20 such prior locking mechanism, however, the roll-back is so arranged as to be capable of turning or swinging movement through only approximately three hundred degrees, or something less than a complete revolution. 25 As a consequence a cylinder lock of that kind upon one side of a door becomes inoperative or ineffective as soon as the dead bolt is thrown in one direction or the other by similar locking mechanism or a latch or 30 handle-operated device on the other side of the door, due to the inability of the roll-back to either pass the dead bolt and reach the swinging latch or to pass around the back or far arc of travel and reach the 35 swinging latch from the other side.

The object of the present invention is to provide improved roll-back mechanism for a cylinder lock of the kind described capable of being swung or turned through a complete arc of three hundred and sixty degrees 40 so that a lock on one side of the door is unaffected by manipulation of the dead bolt from the other side of the door.

Further objects of the invention are in 45 part obvious and in part will appear more in detail hereinafter.

In the drawings, Fig. 1 represents a face view of locking mechanism embodying the invention as applied to a door, the casing 50 cover being omitted for simplicity of illustration; Fig. 2 is a similar view showing the dead bolt partly moved to locking position; Fig. 3 is a detail section on the line 3-3; Fig. 2; and Fig. 4 is a detail sectional elevation on the line 4-4, Fig. 3.

Referring to the drawings, 1 represents a portion of the casing of an ordinary door lock in which are mounted the usual dead bolt 2 and a pivoted-spring latch or tumbler 3, a tongue 4 of which projects through a 60 recess in the dead bolt for engagement by the roll-back or dog, as is usual. 5 represents generally the cylinder lock, comprising a cylinder or barrel 6 and a plug 7 rotatable therein and provided with an opening to receive the key 8. Cylinder and plug members 6 and 7 are concentric or co-axially related, as shown, and otherwise may be of any suitable form. They are provided with the usual key-controlled tumblers and slots 65 arranged in any suitable manner so that the plug may be rotated in the cylinder 6 by insertion and manipulation of the key. For example, the tumblers and interconnecting parts of the plug and cylinder may be of the 70 form illustrated in my prior applications for cylinder lock, one filed January 13, 1922, Serial No. 528,952, and the other filed of even date herewith, to which reference may be had for a more complete description if 75 necessary. The drawings illustrate the parts as of the form in my prior application filed of even date herewith.

As is usual the cylinder is inserted into an opening in the lock casing with its longitudinal axis transverse to the direction of movement of the dead bolt and is so held by a locking screw 9. The roll-back or dog is indicated at 10. It comprises an arm pivoted at 11 on a pin carried by a circular 80 supporting plate or wall 12 lying in a plane normal to the axis of the plug and attached to the cylinder by a connecting bridge 13, being otherwise free of connection to the cylinder. The pivot pin 11 is eccentric to 85 the axis of the plug and cylinder. Said arm 10 has a slot 14 extending lengthwise thereof and also in a direction intersecting the pin 11. Into said slot extends a crank pin integral with or attached to a portion such as 100 a flange, of the rotatable plug 7. This pin is so located on the plug as to be radially more distant from its axis than is the pin 11 so that the latter pin 11 lies within the circle of rotation of pin 15. The operation 105 is as follows:

Fig. 3 illustrates the door provided with two cylinder and plug locks in axial alignment with each other. For the purposes of this application it may be assumed that the 110

two locks are identical as to keys, tumblers and roll-back devices so the description of one suffices for both. Referring to Fig. 1 the roll-back there shown is in such position that counter-clockwise rotation thereof pushes back the latch 3 and moves the dead bolt to locking position, Fig. 2 showing it partially so thrown. However, referring to Fig. 1, if the latch 3 is released and the dead bolt is thrown by the roll-back of the other cylinder lock axially aligned with the one shown in Fig. 1, the roll-back 10 shown in Fig. 1 cannot be moved in the counter-clockwise direction but can only be caused to become effective upon the latch and dead bolt by being turned in the clockwise direction to swing past and inside of the bridge 13. In this manner each of the two locking and roll-back devices shown is wholly independent of the other. Obviously the mechanism on the inside of the door for throwing the bolt need not be a cylinder plug and roll-back as illustrated, but might be an ordinary latch or knob-controlled lever or device as is customary.

Other advantages of the invention will be obvious to those skilled in the art.

What I claim is:

1. Cylinder lock mechanism, comprising relatively rotatable cylinder and plug members, a supporting portion spaced therefrom and lying in a plane substantially normal to the axis of said plug, a roll-back pivoted on said supporting portion, and a crank member rigidly carried by said plug for actuating said roll-back.

2. Cylinder lock mechanism, comprising relatively rotatable cylinder and plug members, a support carried by said cylinder member and having a portion spaced therefrom and lying in a plane substantially 40 normal to the axis of said plug, a roll-back pivoted on the spaced portion of said support, and a crank member on said plug for actuating said roll-back.

3. Cylinder lock mechanism, comprising concentrically related cylinder and plug members, a supporting portion spaced therefrom and lying in a plane substantially normal to the axis of said plug, a roll-back pivoted 50 on said supporting portion on an axis eccentric to the cylinder axis, and a crank pin rigidly carried by said plug for actuating said roll-back and located outwardly from the cylinder axis beyond the center of rotation of said roll-back.

4. Cylinder lock mechanism, comprising concentrically related cylinder and plug members, a support beyond the end thereof, a roll-back pivoted on said support on an axis eccentric to the cylinder axis, and a crank pin rigidly carried by the plug for actuating said roll-back and located outwardly from the cylinder axis beyond the center of rotation of said roll-back, said 60 roll-back having an elongated slot within which said crank pin is longitudinally movable.

In testimony whereof I hereby affix my signature.

JAMES A. MUZZIO.
